TIME-LIMIT RELAY.

1,288,626.

Specification of Letters Patent. Patented Dec. 24, 1918.

Application filed July 7, 1914. Serial No. 849,448.

To all whom it may concern:

Be it known that we, DAVID L. LINDQUIST, a subject of the King of Sweden, and DAVID C. LARSON, a citizen of the United States, both residing in Yonkers, county of Westchester, and State of New York, have invented a new and useful Improvement in Time-Limit Relays, of which the following is a specification.

10 Our invention relates to time limit relays, and has for an object the provision of a simple, practical and efficient circuit controlling device which may have a general application, but which is particularly 15 adapted automatically to protect an electric motor or other apparatus from damage caused by long continued overload or an abnormally heavy current flow.

The accompanying drawings illustrate a 20 preferred embodiment of our invention, in which Figure 1 is an elevation view of the device showing its application to an electric motor; Fig. 2 is a side elevation view of the device in part section; Figs. 3 and 4 are 25 detail views in elevation and side section, respectively, of the relay contact when the same is in its normal position; Figs. 5 and 6 are detail views similar to Figs. 3 and 4, respectively, and showing the relay contact 30 in its operated position.

Like reference characters denote similar parts in all of the figures.

Referring to the drawings, it will be seen that the device comprises a cast iron base 35 1 which is provided with lugs 2-2, by means of which the same may be secured to a wall or switchboard or other suitable place. The upper part of the base forms a magnet frame 3 which incloses a solenoid 4, comprising a stationary adjustable core 5, and a 40 movable core 6. The upper end of the core 6 is preferably tapered as shown, while the adjacent end of the core 5 contains a corresponding tapered recess. A screw-threaded 45 rod 7 is secured to the core 6 by means of an eye 8 and pin 9, and this rod carries upon it a diamond shaped cam member 10 which may be adjusted upon the rod 7 and locked in place by means of the nuts 11. 50 The lower end of the rod 7 is secured to a dashpot piston 12 by means of a pin 13. The piston 12 fits snugly into a dashpot 13 which normally rests upon a shelf 26 and is preferably filled with a light grade of oil, 55 whose consistency is substantially unaf-

fected by variations in temperature. The back of the dashpot is provided with a boss in which are two parallel grooves 15, 15, which embrace a pair of slides 16 formed on the base 1, the construction being such 60 that the dashpot may be moved bodily upon the slides 16, 16, in a vertical direction. Partially surrounding the dashpot are a number of arc shaped removable rings 17, 17, which are for the purpose of weighting 65 the dashpot to any desired amount by adding or taking away one or more of the rings. A by-pass or port 18 extends from the top to the bottom of the dashpot cylinder and permits the oil therein to be displaced upon 70 a movement of the piston, the rate of displacement being controlled by means of a throttling screw 19 which may be adjusted to restrict the port 18 to any degree desired. The cover 20 of the dashpot is concave and 75 extends a considerable distance within the dashpot cylinder. The adjacent parts of the cover and piston are similarly shaped so that the resistance offered by the oil to the upward movement of the dashpot piston, 80 gradually increases as the piston rises in the cylinder. A bracket 21 is secured to the base 1 above the dashpot, and this bracket is provided with a screw threaded boss 22 upon which is an adjustable nut 23. A compression spring 24 bears against the nut 23 and a nut 25 on the rod 7 and the same tends to maintain the rod 7 and dashpot piston 12 in their downward position against the pull of the magnet 4. A cover 42 completely incloses and protects the working 85 parts of the device.

The contact device that co-operates with the cam member 10 is shown in detail in Figs. 3, 4, 5 and 6, and comprises an insulated block 27 which is secured to the base 1. The contact comprises a strip 28 of spring bronze or other suitable metal which is bent back on itself and one end is provided with an insulated roller 29 which 100 bears against the cam member 10. The other end of the spring contact 28 is bifurcated so as to form two contacts 30 and 31 which normally are pressed in electrical engagement with corresponding adjustable stationary contacts 32 and 33, respectively, which are removed from each other and form between them a rectangular groove 34 in which the spring contact 28 may slide. The latter also is in sliding engagement 105 110

with an adjustable block 36 containing a groove 35 in which the spring contact lies. A stop pin 37 is adapted to limit the movement of the spring contact in one direction. 5 Integral with the arm of the spring contact carrying the roller 29, is a member 38 against which lightly bears one end of a spring pressed stop pin 39.

The operation of the contact device alone 10 is as follows: Assuming the parts to be in their normal position as shown in Figs. 3 and 4, and the cam member 10 to be slowly moved upwardly. As the roller 29 rides upon the inclined upper part of the cam, 15 the spring contact 28 will be compressed until finally the peak of the cam passes beyond the roller. As soon as this takes place, the roller at once runs down the lower inclined part of the cam, carrying with it the 20 spring contact, and the latter assumes the position shown in Figs. 5 and 6. By this operation the bifurcated ends of the spring contact 30 and 31 are quickly snapped out of engagement with the stationary contacts 32 and 33, respectively, and take up a position 25 on the insulated block 40 as shown in Figs. 5 and 6, so that any circuit that previously included the contacts 30, 31, 32 and 33 is immediately interrupted. Should the 30 cam member 10 be moved downwardly, the roller 29 rides upon the lower inclined part of the cam, and as soon as the peak of the cam has passed away from the roller the latter immediately runs up the upper inclined part of the cam and the contact 35 spring is snapped back into its original position as shown in Figs. 3 and 4. By reason of this construction, we are enabled to effect a substantially instantaneous make-and-break of the circuit controlled by the contact spring 28 regardless of the speed with 40 which the cam may be moved. The spring contact will operate the instant the peak of the cam moves away from the roller 45 29 and the speed with which it will move depends largely upon the inclination of the cam faces and the tension to which the spring contact is subjected, and if these parts are constructed in substantially the 50 same proportion as shown in the drawings, the action of the spring contact will be to all practical purposes instantaneous, which of course is most desirable, in that it prevents the formation of an arc as the contacts pass out of electrical engagement 55 with each other.

When the device is used to protect a motor, we prefer so to arrange the parts that after the circuit is once opened by the upward movement of the cam 10 a subsequent downward movement of the cam will not return the contact spring to closed circuit position, but rather that this spring contact must be returned by hand. In order to effect 60 this result we provide the stop pin 39,

which automatically falls into position in front of the member 38 (see Figs. 4 and 5) when the spring contact is moved to open circuit position, and thus prevents the automatic return of the latter. Upon pulling 70 out the milled head of the stop pin 39, the spring contact may be returned to closed circuit position by hand.

Referring once more to Figs. 1 and 2, we will describe the operation of the device 75 when used to protect an electric motor. In this case the winding of the magnet 4 is of low resistance and is connected in series with the armature circuit of a motor 42. A main line switch 41 controls the motor circuit, and the operating or holding magnet of this switch is connected in series with the contacts of the relay across the line. If the motor be operating at normal load, the magnet core 6 and connected cam member 80 10 will not be raised against the action of the compression spring 24. If, however, the motor should be subjected to excessive current flow, the magnet 4 becomes powerful enough to overcome the spring 24 and the 85 cam 10 is carried upwardly to effect the opening of the relay contacts as already described. The opening of these contacts 90 interrupts the holding circuit of the switch 41 and the latter opens the line circuit and cuts 95 off the current to the motor and all the parts of the device with the exception of the spring contact 28 return to normal position.

Thus far, nothing has been said descriptive of the time limiting feature of the relay. 100 This feature of the invention is most important and resides in the novel arrangement of the dashpot.

As is well known, it is permissible, and under certain conditions desirable to permit excessive current to flow to a motor for a limited time, the strength of this current being such that if the same were allowed to flow for any considerable length of time the motor windings might be damaged. The 105 usual type of overload circuit breaker does not permit of this condition, since it is set to operate at a predetermined overload and will open the motor circuit immediately this 110 overload condition is reached. With the device herein disclosed the electric motor is permitted to withstand a certain overload for a predetermined length of time and at the expiration of that time the motor circuit is at once opened. In case of an unusually 115 heavy overload or a short circuit the main line circuit to the motor is immediately opened. The manner in which we effect this result is as follows: Assume that the various parts of the device are in the position shown in Fig. 1, and the motor 42 becomes moderately overloaded. The core 6 of the relay tends quickly to raise the cam member 10, but this movement is opposed by the spring 24 and the retarding action of the dashpot 120 125 130

piston, with the result that the cam 10 moves slowly upwardly until the high part of the cam passes beyond the roller 29, whereupon the spring contact 28 immediately effects the 5 opening of the motor circuit. Since the retarding action of the dashpot may be controlled by restricting the by-pass or port 18, the time interval between the initial movement of the magnet core and the time at 10 which the high part of the cam passes beyond the roller 29 may be accurately determined so as to effect the desired results.

It will be observed that the upward movement of the dashpot piston tends bodily to 15 carry the dashpot with it, but when the overload on the motor is moderate this tendency is successfully resisted by the weight of the dashpot assisted by the weighted rings 17, 17, and the dashpot is not moved. If, 20 however, the overload on the motor is excessive or a short circuit should exist, the upward pull on the magnet core 6 is sufficiently powerful to raise both piston and dashpot cylinder as a unit, with the result 25 that the function of the dashpot becomes *nil*, and the spring switch is immediately opened so as to cut off the motor circuit.

Under some conditions it is desirable that the upward movement of the magnet core 30 and connected parts shall be at a constant slow speed throughout its entire stroke. In order to attain this result, the dashpot is so arranged that its retarding action increases as the piston rises which just compensates 35 for the increased pull of the magnet core as the latter moves upwardly and the resistance of its magnetic circuit decreases. The variable retarding action of the dashpot is due to the increasing choking of the fluid 40 between the dashpot piston and the adjacent portion of the dashpot cover as the piston moves upwardly. The coacting ends of the magnet cores 6 and 5 are tapered in order that the variable pull of the core 6 as it 45 moves upwardly may be more nearly uniform than if the adjacent ends of the cores were made flat as is the usual practice.

Our invention may be used to advantage 50 for controlling any desired circuit, and in case the time-limiting feature is not desired, the dashpot may be dispensed with. If it is desired that the relay shall directly control a circuit carrying a substantial current rather than employ an intermediate device, 55 such as the switch 41 of Fig. 1, it becomes necessary merely to increase the current carrying capacity of the spring contact. The device is simple, and requires but few parts. All troublesome triggers, latches and trips 60 are dispensed with, and the result is a most practical and efficient mechanism admirably suited for a great many different purposes.

While we have disclosed herewith a preferred embodiment of our invention, we desire not to be limited to the precise construc- 65

tion and arrangement of parts herein shown and disclosed, since it is obvious that one skilled in the art could readily suggest changes without departing from the spirit and scope of the invention.

70

What we claim is:—

1. An electro-responsive device comprising a solenoid and movable core, a fluid dashpot connected with the core, and means for effecting a variable retarding action of 75 the dashpot whereby the solenoid core is constrained to move at a uniform rate of speed throughout its range of movement.

2. A relay comprising a solenoid and movable core, a retarding device connected with 80 the core, means for effecting a variable action of said retarding device whereby the solenoid core is constrained to move at a uniform rate of speed and a quick-acting circuit-controlling device operated by said 85 core.

3. A relay comprising a solenoid and movable core, a retarding device connected with the core, means for effecting a variable action of said retarding device whereby the 90 solenoid core is constrained to move at a uniform rate of speed, a switch controlled by said core, and means for effecting a quick action of said switch regardless of the rate of movement of the said core.

4. A time limit relay comprising a solenoid, a movable core therein, contacts controlled by the core, a fluid dashpot retarding device for the core, and means for preventing bodily movement of said dashpot 100 except upon excessive current flow in said solenoid.

5. A time limit relay comprising a solenoid, a core movable therein, contacts controlled by the core, a piston connected with 105 the core, a dashpot cylinder for the piston, and means for preventing a bodily movement of both piston and cylinder except upon a predetermined excess current flow in the solenoid.

6. A time limit relay comprising a solenoid, a core movable therein, contacts controlled by the core, a piston connected with the core, a dashpot cylinder for the piston, and means for maintaining said cylinder 115 against movement during normal flow of current in the solenoid but permitting said cylinder and piston simultaneously to move upon excessive current flow in the solenoid.

7. A time limit relay comprising a solenoid, a core movable therein, contacts controlled by the core, and a retarding device for the core comprising a dashpot normally held against movement but permitted bodily to move upon abnormal current flow in the 125 solenoid.

8. A time limit relay comprising a solenoid, a core movable therein, contacts controlled by the core, a dashpot adapted bodily to move, a piston in the dashpot connected 130

to the core, and removable weights associated with the dashpot for normally maintaining the latter against movement while permitting the dashpot bodily to move upon 5 abnormal current flow in said solenoid.

9. A time limit relay comprising a solenoid, a core movable therein and connected to a piston, a dashpot for retarding the piston and core, slides upon which the dashpot is adapted to travel, means normally for holding the dashpot against movement as the piston is moved by the core but permitting the dashpot bodily to move upon an abnormal current flow in the solenoid, and 15 a quick-acting switch controlled by the core.

10. A time limit relay comprising a solenoid, a core movable therein and connected to a piston, a dashpot for retarding the piston and core, slides upon which the dashpot is adapted to travel, means comprising 20 a plurality of removable weighted rings as-

sociated with the dashpot normally for holding the dashpot against movement as the piston is moved by the core but permitting the dashpot bodily to move upon an abnormal current flow in the solenoid, and a quick acting switch controlled by the core. 25
